CAMERA FLASH MOUNTING BRACKET

Peter T. Quinn, and Dean M. Peterson, Littleton, Colo.,
assignors to Honeywell Inc., Minneapolis, Minn.

Filed June 12, 1972, Ser. No. 262,018

Term of patent 14 years

Int. Cl. D16—05
U.S. Cl. D61—1 E

FIG. 1

FIG. 2

FIG. 3

FIG. 4

FIG. 5

FIG. 6

FIG. 7

FIG. 8

FIG. 1 is a top plan view of a camera flash mounting bracket showing our new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a lower front perspective view thereof, the flash unit connector having been omitted for convenience of illustration; and

FIG. 8 is a lower front perspective view thereof with the flash unit holder in a detached position.

We claim:

The ornamental design for a camera flash mounting bracket, as shown and described.
